UNITED STATES PATENT OFFICE

GEORGE I. BOHMAN, OF NEW YORK, N. Y.

LID CLAMP FOR CONTAINERS

Application filed April 6, 1932. Serial No. 603,588.

This invention relates to lid clamps for containers and has for an object to provide an improved construction particularly adapted for large containers, as, for instance, garbage cans, ash cans, and the like.

Another object is to provide an improved lid clamp which is secured to a container and left in place until the container has been worn out, the structure including a spring actuated 10 arm capable of being moved to one side when the lid is to be removed and to be moved to a point on top of the lid when in functioning position.

A further object, more specifically, is to 15 provide a lid clamp for garbage containers and the like wherein a supporting bracket is provided adapted to be connected to the container and carrying a rotating and reciprocating rod secured to or merging into the 20 clamping handle, the rod and bracket being connected by a spring which acts to clamp the arm against the lid on the container when in one position, and acts to hold the arm against the side of the container when in a 25 second position.

In the accompanying drawing,—

Figure 1 is a view partly in vertical section and partly in elevation showing a well known construction of container used for 30 ashes, garbage, and the like, and a lid clamp embodying the invention applied thereto, the lid clamp being shown in side elevation.

Figure 2 is an enlarged fragmentary sectional view through part of the container 35 and part of the lid clamp illustrated in Figure 1.

Figure 3 is a top plan view of the structure shown in Figure 1 with the lid removed, the view illustrating how the clamping arm 40 rests against the side of the container when not in use.

Referring to the accompanying drawing by numerals, 1 indicates a container, as, for 45 instance, a garbage can or ash can, the same being of a well known construction, having a metal reinforcing band at the bottom and a similar ring 3 at the top which is held in place by the rivets 4. A lid 5 is also shown in Figure 1, the same being old and well known,

and provided with a downwardly extending flange 6 which slides over the ring 3.

In many places, as, for instance, in New York city, it is against police regulations to leave garbage cans or containers open when placed on the street or outdoors ready to be emptied. In many instances, the lid is removed after having been properly placed on the container, as, for instance, by mischievous children, by the wind, or under some circumstances, by dogs. Regardless of how the lid is removed the law in some places states they must remain in place, and if an official finds the lid removed, it makes the owner of the container liable to arrest. To avoid this condition in respect to large apartment houses, and elsewhere, the present invention has been produced and constructed to positively hold the lid in place unless removed by someone sufficiently strong to manipulate the lid 70 clamp.

As shown in Figure 1, the arm 7 presses against the upper part of the lid 5 and holds the same against accidental removal or removal from the various causes above outlined. This arm may be integral, as shown, or may be separate and rigidly secured to the vertical rod 8 which extends loosely through apertured sections 9 and 10 of the bracket 11. The bracket 11 is not only provided with sections 9 and 10 but with a connecting bar 12 and with end projections 13 and 14. When mounting the device on a container, one of the rivets 4 is removed, and if the container should be formed without rivets, a hole is drilled or punched through which the bolt 15 extends, said bolt having its head made comparatively thin so that there will be a slight projection, but not enough to prevent the lid 5 from readily sliding into position, as shown in Figure 1. It is, of course, evident that if desired the ring 3 could be countersunk to take care of the head of the bolt 15 without departing from the spirit of the invention. The extension 13 may be secured in place in other ways also without departing from the spirit of the invention.

As shown in Figure 1, the extension 13 is slipped in between the ring 3 on the body of 100

the container, and then the bolt 15 is applied. Suitable holes are provided by drilling or punching or otherwise, in the desired point in the container 1 for the reception of the respective bolts 16.

As shown particularly in Figure 2, rod 8 between the sections 9 and 10 is surrounded with a spring 17 having an end 18 fitted into the aperture 19 in section 9, while the end 20 is fitted into the aperture 21 in the ring or abutment 22, which is secured rigidly to the rod 8 by any desired means, as, for instance, by a pin 23.

When the device is functioning fully, the parts assume the position shown in Figure 1, and in this position, the curved portion 24 of the arm 7 presses against the top of the cover 5 through the action of spring 17 and associated parts. This will resiliently lock the cover 5 in place. When it is desired to remove the cover 5, arm 7 is swung to one side and as soon as it is free of the cover 5, it will automatically move downwardly under the action of spring 17 until it assumes the dotted position shown in Figure 1, and the position shown in Figure 3. The spring 17 is slightly wound so that it gives a continuous tendency to the rod 8 to rotate, and, consequently, resiliently presses the arm 7 against the side of the container below the upper edge, whereby the arm is out of the way, but is in a position to be used at any time. When the lid is to be placed on the container, arm 7 is swung outwardly a short distance and the lid deposited into its proper place, after which the arm 7 is pulled upwardly and then swung around to the position shown in Figure 1.

I claim:

1. A lid clamp for containers comprising a bracket adapted to be connected to the container at spaced points, said bracket having spaced aligned apertures, a rod extending through said aligned apertures pivotally supported by the bracket, an arm carried by said rod at one end, said bracket being positioned with the upper end below the upper edge of said container so that the arm may swing over the cover when in an operative position and when in an inoperative position lowered and swung against the side of the container, and means acting on the bracket and arm for causing the arm to lock the cover on the container when in an operative position and pressed against the side of the container when in an inoperative position.

2. A lid clamp for containers comprising a bracket adapted to be connected to the container, a rotatable arm carried by the bracket adapted at one time to be arranged along the side of the container, and at another time to extend over the lid of the container, and spring means connected at one end to the bracket and at the other end to the arm for forcing the arm at one time to press against

the lid axially of the container and press the lid against the container and at another time to press against the side of the container transversely of the container.

3. A container lid clamp including a substantially U-shaped bracket having a pair of aligned apertures, a rod rotatably mounted in said apertures, a lid clamping arm carried by said rod, and double-acting spring means acting when in one position on the rod and bracket for causing said arm to press against said lid axially of the container and when in a second position to swing said arm laterally against the side of the container.

4. The combination of a container provided with a lid of means for clamping the lid on the container, said means including a bracket secured at its respective ends to the container, said bracket being provided with a pair of aligned apertures, a rod rotatably mounted in said apertures, a lid clamping arm carried by said rod at the upper end, said arm being swingable with the rod so as to rest on top of the said lid in one position and to be on one side of the lid in a second position, and a double-acting spring acting on said rod and said bracket for causing said arm when in one position to press against said lid, and when in a second position to act on said rod and arm to cause the arm and rod to be lowered and the arm positioned and swung laterally to press against the sides of the container.

5. A lid clamp for containers comprising a substantially U-shaped bracket, means for connecting the respective ends of the bracket to the sides of the container, the upper ends of the bracket spaced below the top of the container, said bracket having a pair of aligned apertures, a rod slidably and rotatably mounted in said apertures and positioned to extend parallel to the sides of the container, a spring surrounding said rod having one end connected to the rod and the other connected to the bracket whereby the spring will give the rod a tendency to move downwardly and also to swing laterally, and an arm carried by the upper end of said rod positioned to press against the lid of the container and cause the same to press against the top of the container when the arm is in functioning position, said arm and rod being swingable laterally manually and then movable downwardly by said spring, said spring acting to exert a torque on said rod and arm for causing said arm in its lowered position to press against the side of the container.
